UNITED STATES PATENT OFFICE

ANTON J. YEAGER, OF WISCONSIN RAPIDS, WISCONSIN, ASSIGNOR TO PRENTISS-WABERS PRODUCTS CO., OF WISCONSIN RAPIDS, WISCONSIN, A CORPORATION OF WISCONSIN

VAPOR-STOVE CONSTRUCTION

Application filed March 28, 1929. Serial No. 350,532.

This invention relates to a new and improved vapor stove construction, and more particularly to the construction of a generator for such stoves designed for instant lighting.

This invention relates to the type of vapor stoves which utilize gasoline or similar volatile fluids as a fuel, and vaporize the gasoline so that it is burned in burners of the wick-less type. Such stoves have heretofore been provided with a variety of means for causing the initial vaporization of the fuel in starting the stove. It has been considered essential that fuel be vaporized by heat in order that the stove may be started, and this heat has been secured in a number of different ways.

With some forms of stove a generating cup is provided located below the generator valve or generator pipe, and some of the liquid fuel is placed in the cup and lighted to heat the generator. A form called a "match lighter" has been developed in which a separate small generating valve is heated by holding a match under it, whereupon it may be opened to deliver a small flame which in turn heats the large generator valve. The large generator valve is then turned on and when heated, the small generator, heated by the match, is turned off. All of these various forms of lighters or preheaters involve several steps on the part of the person operating the stove and an appreciable delay before the stove is ready for service.

It is an object of the present invention to provide a construction wherein the stove may be instantly lighted without any preheating.

It is an additional object to provide a construction of this character in which initial combustion is carried on with a mixture of air and fuel under pressure, the air and fuel coming from the fuel tank of the stove.

It is a further object to provide a construction in which means are provided for preventing the deposition of fuel in the generator from the mixture of fuel and air.

It is an additional object to provide a mixing valve construction wherein the orifices controlling the flow of air under pressure

and the flow of fuel, are readily accessible for cleaning or adjustment.

Other and further objects will appear as the description proceeds.

I have shown a preferred embodiment of my invention in the accompanying drawings, in which—

Figure 1 is a side elevation of an assembly of generator, fuel tank and valves with a stove burner;

Figure 2 is a plan view of the assembly shown in Figure 1;

Figure 3 is a longitudinal section through the generator valve; and

Figure 4 is a section taken on line 4—4 of Figure 1.

Referring first to Figures 1 and 2, the fuel tank 11 is of usual construction and is shown as provided with a filling opening 12 and with a valve 13 provided with a threaded end 14 which may be connected with any suitable source of compressed air. A double meter 15 is provided with a scale 16 and corresponding pointer for indicating the amount of fuel in the tank and with a second scale 17 and corresponding pointer for indicating the air pressure in the tank.

A mixing valve 18 is threaded into a flange 19 in the top of the tank, and is provided with a valve stem 20 and valve handle 21. This valve 18 is connected to a fuel pipe 22 which is connected by means of elbow 23 to the T 24, which is threaded into the top of the tank and is provided with an inner extension, not shown, which extends adjacent the bottom of the tank. This T 24 has connected thereto the main fuel valve 25 provided with a handle 26. The valve 25 is connected by a pipe 27 with a threaded nipple 28 extending from the generator body member 29. This member 29 is provided with a lug 30 for securing the generator assembly to a fixed portion of the stove. The member 29 has a tubular member 31 threaded therein and is also provided with a valve stem 32 and valve handle 33. The body member 29 is also connected by pipe 34 with the mixing valve 18.

Referring now to Figure 3, which shows the generator assembly more in detail, the valve stem 32 has a threaded portion 35 which

is threaded into an inner reduced portion 36 of the tubular member 31. The member 32 is provided with the slots 37 to facilitate passage of the fuel and air past these threaded portions. The member 32 has a reduced portion 38 fitted in an enlarged cavity 39 adjacent the end of the tubular member and is provided with the shoulder 40 bearing against a valve seat 41 in the member 31. Past the shoulder 40 is located the reduced portion 42 fitted in the reduced end 43 of the member 31. The portion 42 also carries the needle-like extension 44 which passes through a small opening in the end of the discharge member 45. The coil spring 46 surrounds the central portion of the valve stem 32 and is held in place by pin 47 extending through the valve stem. The pipe 27 is shown as secured to the threaded nipple 28 by the threaded sleeve 48 and this pipe 27 has threaded therein the cap 49 which is provided with the calibrated orifice 50 through which the fuel passes and enters the generator valve through the opening 51. As best shown in Figure 1 the pipe 34, which carries the mixture of fuel and air to the generator valve, is similarly secured to the lower portion of the member 29 by means of a sleeve 52.

Referring now to Figure 4, the mixing valve body 18 is shown threaded into the bushing 19 which is secured in the top of the gas tank 11. The lower portion 53 of the member 18 which is threaded into this bushing 19, carries in its lower end the plug 54 which is provided with the calibrated orifice 55. This orifice permits the air under pressure in the top of the tank to flow through chamber 56 and passage 57 into the mixing chamber surrounding the valve stem 20. The valve stem 20 is provided with a conical head 58 adapted to seat against a valve seat 59 formed in the mixing valve body member 18. The passage 60 beyond the valve seat 59 leads to the pipe 34, which is connected to the generator body member 29. The pipe 22 which is adapted to lead fuel to the mixing valve is connected to the elbow 61 which is threaded into the upper extension 62 of the valve member 18. This extension 62 carries the plug 63 threaded therein, this plug being provided with the calibrated orifice 64.

As shown in Figures 1 and 2, the generator tube 31 is adapted to discharge into the mixing tube 65 which leads through passage 66 to the burner 67. An orifice 68 is provided for the introduction of additional air to mix with the discharge from the generator tube. It will be understood that any number of additional burners may be connected to the tube 65 and any suitable valves may be provided for the control of the various connections.

In operation of the stove constructed according to my invention, the tank 11 will be provided with fuel and with air located in

the tank above the fuel, under suitable pressure. The valve handle 21 is then opened to withdraw the valve stem 20 so as to unseat the valve 58 from its seat 59. This permits air under pressure to flow up through the orifice 55, chamber 56 and passage 57 into the chamber around the valve and past the valve seat and out through pipe 34. If the fuel tank is in a warm room this air will carry with it a certain amount of entrained gasoline vapors. The unseating of the valve 58, however, also permits liquid gasoline to come up through the T 24 and through pipe 22 down through the orifice 64 into the mixing valve chamber and to pass out through pipe 34 mixed with the air.

It will be apparent that it is only necessary to turn this one valve as the main fuel supply valve 25 is located beyond the T 24. There will now be a mixture of fuel and air flowing through pipe 34 to the generator valve member 29. In order to permit the flow of this mixture into the mixing tube 65 out of the orifice at the end of the generator tube, the generator valve handle must be rotated to unseat valve 40 from the valve seat 41 adjacent the discharge end of the generator tube. The mixture of fuel and air then flows around the valve stem 32 and out past the control needle 44. It will be noted that the spring 46 or other spiral member inserted at this point causes the fuel and air to take a tortuous passage. It also reduces the effective flow area for the fuel and air and thus increases their velocity and prevents the deposit of solid fuel at this point.

The mixture of gas and air is further mixed with additional air in the mixing tube 65 and may be immediately lit by touching a match or other lighting means to the burner 67. The burner 67 is located below the generator tube member 31 and serves to heat this member. As soon as this member has been heated the valve 21 may be closed and the main fuel supply valve 26 opened. This cuts off the supply of a mixture of fuel and air for the generating valve and causes a supply of liquid fuel. This fuel, however, is gasified in the tube 31 and is mixed with air in the mixing tube 65 and supplies the proper combustible mixture to the burner 67.

The orifices in the mixing valve may be so proportioned as to supply an adequate amount of combustible mixture to a single burner such as the burner 67. This will not take an excessive amount of air from the pressure fuel tank if the burner is only operated in this manner sufficiently long to adequately heat the generator valve tube 31. After this tube is heated and the stove is taking liquid fuel through the regular valve, such additional burners as desired may be provided with fuel by any suitable valves and stove connections which have not been shown.

It will be understood that the calibrated orifices in the mixing valve are very fine and permit a relatively small flow. These orifices are located where they may be readily accessible so that they may be cleaned should they become clogged with impurities from the fuel or air. The location of the plugs carrying these orifices is an important feature of the invention.

10 While I have shown one preferred form of my invention by way of example, it is capable of being embodied in other forms and I contemplate such changes and modifications as come within the spirit and scope of the appended claims.

15 I claim:

1. In a vapor stove, a pressure fuel tank, a mixing valve connected to the air under pressure in the top of the tank, a connection between the mixing valve and the liquid fuel in the tank, a generator, a connection between the mixing valve and the generator, and a separate valve controlled connection between the generator and liquid fuel in the tank.

20 2. In a vapor stove, a tubular generator having a discharge end, an adjustable valve member extending lengthwise of the tubular member, valve controlled means for admitting a mixture of fuel and air to the generator and separate valve controlled means for admitting a liquid fuel to the generator.

25 3. In a vapor stove, a pressure fuel tank, a mixing valve, a mixing chamber in said valve, a connection between the mixing chamber and the liquid fuel in the tank, a separate connection between the mixing chamber and the air under pressure in the tank, a tubular generator, a valve controlled passage from the mixing chamber to the generator, and a valve controlled passage from the generator to the liquid fuel in the tank.

40 4. In a vapor stove, a pressure fuel tank, a mixing valve having a mixing chamber therein, separate connections from the chamber to the air in the fuel tank and to the liquid fuel in the fuel tank, plugs having calibrated orifices for controlling the flow of fuel and of air to said mixing chamber, a generator, a valve controlled connection from the mixing chamber to the generator, and a connection from the generator to the liquid fuel in the tank.

45 Signed at Wisconsin Rapids, Wisconsin, this 26th day of March, 1929.

50 55 ANTON J. YEAGER.
